(No Model.)

J. P. WILSON.

CAR COUPLING.

No. 352,104.

Patented Nov. 2, 1886.

UNITED STATES PATENT OFFICE.

JOHN P. WILSON, OF POUGHKEEPSIE, NEW YORK, ASSIGNOR TO GERALDINE B. WILSON, OF SAME PLACE.

CAR-COUPING.

SPECIFICATION forming part of Letters Patent No. 352,104, dated November 2, 1886.

Application filed April 27, 1886. Serial No. 200,346. (No model.)

To all whom it may concern:

Be it known that I, JOHN P. WILSON, a citizen of the United States, residing at Poughkeepsie, in the county of Dutchess and State of New York, have invented certain new and useful Improvements in Car-Couplers; and I do hereby declare the following to be a full, clear, and exact description of the invention, such as will enable others skilled in the art to which it appertains to make and use the same.

My invention relates to car-couplers; and it consists in the construction and arrangement of the parts of the same, which will be more fully hereinafter described, and definitely pointed out in the claims.

My invention is an improvement on the coupler shown and described in the application of J. G. Slater, filed February 20, 1886, Serial No. 192,645.

The object of my invention is to provide an automatic coupler in which the coupling-pin shall have an easy but positive action, which is simple in its construction, strong and durable, and cheaply manufactured. I attain these objects by the construction of coupler illustrated in the accompanying drawings, wherein like letters of reference indicate similar parts in the several views, and in which—

Figure 1 is a perspective view of a draw-head with my improved coupler applied thereto. Fig. 2 is a longitudinal vertical section of my improved coupler, showing the coupling-pin in two positions in dotted lines. Fig. 3 is a view similar to Fig. 1, showing the coupling-pin in a locking position in dotted lines. Fig. 4 is an elevation of the link-pin.

A represents the draw-head; B, the draw-bar. The draw-head A is provided with a vertical longitudinal slot, b, through which the coupling-pin D passes, said longitudinal vertical slot having transverse slots d' at the top thereof, through which the wrist-pins d", on the coupling-pin D, enter a camway, C, formed transversely to the longitudinal slot b, the walls of said camway being formed of varying curves and inclines, with the front wall perpendicular. These several forms of construction were fully illustrated and described in the application aforesaid, my improvement thereon being as follows:

The front wall, c, is formed perpendicularly to the point c', where the wall is curved to form a seat for the wrist-pins d", when the coupling-pin D is in a locking position. From the point c' a wall, 1, extends upward on an incline to the point 2, from whence a short wall, 3, extends to the point 4, which is inclined into the camway at about right angles to the wall 1. From the point 4 to the point 6 a short wall is formed, and from the point 6 to the point 8 a slight indentation is formed. From the points 2, 4, 6, and 8 the wall is constructed in the form of a projection, the under side of which acts as a stop and prevents the coupling-pin from passing up through the opening b' by a sudden jar or commotion of the link E. From the point 8 an inclined wall extends upward, which merges into and forms one wall of the transverse opening b'.

As heretofore stated, the wall c from the point c' to the point 10 is perpendicular, and from the point 10 to the point 12 the wall is in the form of a rounded projection, 13, and from said projection a concaved curved rest, 15, is formed up to the point 14. From the point 14 a slightly upward curved wall, 17, is formed to the point 16, where the camway again merges into the transverse slot b'. From the point 10 to the point 16 the wall is cut horizontally in relation to the other portion 80 of said wall, except the concaved curved rest 15, which is engaged by the wrist pins d" when it is desired to remove the coupling-pin D entirely from a coupling position.

The superior wall of the link-recess 18 is 85 formed horizontally straight, so that the link E, on entering the said recess, will have a more positive and effective movement with a less amount of incline, so that its full end will strike against the inclined face of the draw-head A with which it is desired to couple.

The coupling-pin D is formed with a single projection, 19, on its lower portion, adjacent to its lower front inclined edge. This projection forms an indentation, which engages with 95 the front wall, b', of the longitudinal vertical slot b when the pin is in a coupled position. The lower front end of the said pin is further braced against the lower front wall of the longitudinal vertical slot b. The rear wall of said 100

slot *b* is formed on an incline and of a contour similar to the rear side of the coupling pin. The coupling-pin *D* is preferably made flat, so that the said longitudinal vertical slot through 5 which the said pin passes can be of narrow construction, being just wide enough to allow the passage of the said pin *D*, thereby causing the wrist-pins *d*³ to accurately engage with the camway *C*. The front wall of the aperture *b* is slightly inclined toward the front of the head, the coupling pin *D* resting against the same in a slightly forward inclined position, thus having a more securely-braced position against the action of the link *E*. An aperture, *d*, is formed near the top of the coupling-pin *D*, in which a small chain, cable, or rope, *d*⁴, is secured, and extends down through staples *a a*, secured to the side of the draw-head *A*, and has a ring, *d*⁵, attached to its 20 lower end, which is of such a size as to prevent it from passing through the said staples *a a*, thereby always keeping the cord *d*⁴ in one place, and in a convenient position for use.

The cord *d*⁴ is of sufficient length to allow 25 the coupling-pin to be removed from the draw-head and at the same time be secured in the draw-head.

The operation of my improved coupler is as follows: The pin *D* being arranged in a lowered position, with its wrist-pins *d*³ resting in the portion of the wall *c*, the incoming link *E* of another car strikes the lower inclined front edge of the said coupling-pin, and raising it in the vertical longitudinal slot *b*, the wrist-pins *d*³ moving upward in the cam-way *C*, allowing the link to pass under the pin. The coupling-pin then drops down by gravity through the link and holds it in a coupled position. When it is desired to uncouple the link, the pin *D* is 30 drawn upward and the link allowed to pass out. When the pin *D* is suddenly forced upward when struck by an incoming link in coupling, the said pin will always remain in position in the vertical longitudinal slot *b*, in consequence of the wrist-pins *d*³ remaining in 35 engagement with the camway, and when the pin rises these wrist-pins strike against the projection formed in the rear wall of said camway, between the points 2 and 4, and prevent 40 the said wrist-pins from passing up into the transverse slots *b*'. By the construction of the rear wall from the points 2 to 4, 4 to 6, 6 to 8, 45

and thence up to the transverse entrances *b*', as described, the coupling-pin *D* will be admitted to the vertical longitudinal slot *b*, with 55 the wrist-pins *d*³ in engagement with the camway, in one position only, and that is when the front portion of the said link-pin is toward the front of the draw-head. By this means the link-pin cannot be inserted in the said 60 slot and camway, except in its operative position. When it is desired to place the coupling-pin in a raised position, the said pin is drawn upward until the wrist-pins thereon engage with the seat 15, formed in the upper wall. 65 When the pin is in this position, the lower point clears the link-recess 18, and the link is left free to enter or withdraw from the said recess in making flying switches, or for any other purpose desired. 70

It is obvious that the walls of the camway may be constructed curved or straight, as may be desired, without in the least departing from the nature and principle of my invention.

Having thus described my invention, what I 75 claim as new, and desire to secure by Letters Patent, is—

1. In a car-coupler, the combination, with a draw-head having a vertical longitudinal slot therein, of a camway extending transversely 80 from each side of the said vertical longitudinal slot, said camway having irregular walls with a rest formed in the upper portion and a projection in the rear portion thereof, a link-pin having wrist-pins engaging with the vertical longitudinal slot and the camway, and a horizontal link-recess, substantially as described, and for the purposes specified.

2. In a car-coupler, the combination, with a draw-head having a vertical longitudinal slot 90 therein and a camway extending transversely from each side of said slot, of a flat coupling-pin engaging with said slot and camway and a cord secured near the top of said coupling-pin, passing down through staples on the outside of the draw-head, substantially as described.

In testimony whereof I affix my signature in presence of two witnesses.

JOHN P. WILSON.
